UNITED STATES PATENT OFFICE.

EDWARD B. CORCORAN, OF CINCINNATI, OHIO.

RADIATOR.

Application filed April 2, 1919. Serial No. 286,861.

To all whom it may concern:

Be it known that I, EDWARD B. CORCORAN, a citizen of the United States, and a resident of Cincinnati, in the county of Hamilton and State of Ohio, have invented certain new and useful Improvements in Radiators, of which the following is a full, clear, and exact description, reference being had to the accompanying drawing, forming part of this specification.

My invention relates to honeycomb type radiators which are made up of sheets of metal corrugated in a special manner and set together so as to form vertical water passages and transverse air passages. Such radiators as used in automobiles are connected at the top with a water tank, and at the bottom with a like tank, and means are provided to cause a circulation of water from the bottom tank around the engine to the top tank and thence down the water passages where it is cooled by the air passing through the transverse air passages.

The metal used in radiators of this type in forming up the core, as the cooling section is called, is uniformly of some copper composition such as brass. This material is quite expensive and hence the saving of a small amount of metal in a radiator is a considerable saving in core construction. One of the objects of my invention is to so construct the metal sheets that they will provide the maximum of cooling area with the smallest amount of brass.

Hitherto there have been efforts made to construct a radiator which had the maximum cooling surface, but in these radiators the embossing and excessive corrugation resulted in a structure which lacked stiffness. Thus I desire herein to provide a radiator of the honeycomb type which has the maximum of stiffness as well as the sufficient cooling surface.

According to my invention herein, I do more than provide a uniform shoulder for the edges of the sheets, as customary in the art, since in every alternate lateral wall of each strip I provide a further transverse depression, which serves to extend the water containing volume of the radiator core when made up, by just the amount of space that is cleared by these extra depressions. The extra depressions also abut against each other, which by the amount of space transverse the core that is taken up, cuts down the number of units necessary to make up

the core and saves brass in the manufacturing.

As will be shown, I also form a central bend in these extra depressions to permit a small space to intervene between the abutting faces of the same, thereby permitting a vertical passage for air, and increasing radiating space.

The above briefly noted features of construction and the details generally of my radiator core, together with its advantages will be hereinafter more specifically pointed out and claimed.

In the drawing,

Figure 1 is a front elevation of a part of the radiator, a portion of which is in section to show the interior construction.

Figure 2 is a vertical section through the core showing in elevation the air tube portions of a unit, and partly broken away at the base to show a water tube portion.

Figure 3 is a detail perspective view of several assembled sheets in the core.

The preferred form of unit used in making up my new core consists of a specially corrugated sheet of metal turned back on itself and lapped over at the ends to form a closed member, although two separate strips could be used to make up one unit. The pieces of metal are preferably rolled out in one operation and then cut in desired lengths, bent double and their ends lapped. The pieces as made up form the air passages and are placed together so as to form water passages, with the air passages horizontal and the water passages vertical. Of course the pieces could be set together diagonally of the completed core, but this would be more expensive to make up.

The strips are rolled out so as to be in the form of a half hexagon, with the lateral faces 1 and 2, and the shoulders 3 terminating in the raised edge portions 4. As constructed so far, the core pieces would correspond to structures which have been in use prior to my invention. In addition to the above folds in the metal, however, I provide for every alternate lateral face, i. e. the faces 2, an additional bending of the metal away from the raised edges, this additional bending extending substantially across from one shoulder to the opposite one, said face 2 being dented in at 5 toward its central point.

The metal strips so rolled are then bent back on each other, and the sides 2 placed

opposite sides 2, so that the extra deep shoulders 2^a formed by the additional bend as above described abut against each other.

A number of the units so formed are then

5 placed together in what might be termed staggered relation with sides 1 of one unit adjacent to sides 2 of the next unit, and with the edges 4 abutting each other closely throughout. The core so made up is dipped 10 in solder which permanently unites the abutting edges, both front and back, and thereby seals up the water passage, which runs vertically between the units as shown at A (Figure 1), the air passages B being 15 through the space intermediate the walls 1 in the units, and air also being permitted a vertical path through the spaces left by the central bend of the walls 2, as shown at C (Figure 3).

20 In Figure 3 are shown parts of two of the units fitted together. It will be noted that by reason of the deep depression 2^a when a single unit is formed, the upper and lower edges of the raised portions 4 which approach each other do not come together but are spaced away by the depressions 2^a which abut each other. These depressions 2^a are a deepening of the shoulders 3. Now when the next unit is placed in staggered relation with the sides 1 of one unit adjacent to the sides 2 of the next unit, by reason of the fact that the approaching sides of each separate unit do not come together, the several units when put together will 30 occupy more space than in the construction of the prior art where the contiguous walls of each unit come much closer together. Moreover when the units are assembled in the alternate relation, the side 2 comes into 35 juxtaposition with the side 1 of the next unit. Extra water space is therefore provided toward each outer portion of the units.

40 Due to the fact that the metal is drawn clear across the strips in forming the faces 2, with their extra deep shoulders 2^a, there is no substantial weakening of the metal, which weakening would undoubtedly be present if mere knobs or buttons were 45 formed in the walls 2, instead of drawing out the entire walls.

The central bends in the walls or faces 2 also permit vertical passage of air through the units, although it cuts down to some extent the water passage intermediate the walls 1 and walls 2 of adjacent units.

50 The extra deep shoulders and the constituent of strength above noted form a strong abutment across the radiator core in

the portion intermediate its ends, whereas, 60 as I am informed, radiators of the past rely upon the raised edges alone for this cross abutment.

Having thus described my invention, what I claim as new and desire to secure 65 by Letters Patent, is:

1. A radiator core comprising units composed of metal strips formed in alternate projections and depressions, and with shoulders adjacent the edges, thereby providing 70 raised edge portions, said strips bent back on each other, and the units set together in staggered relation to form a core, said units having additional depressions formed in their strips inside and adjacent to the said 75 shoulders to provide supports for said core transverse thereof, in addition to said raised edge portions, for the purpose described.

2. A radiator core comprising units composed of metal strips formed in alternate projections and depressions, and with shoulders adjacent the edges, thereby providing 80 raised edge portions, said strips bent back on each other, and the units set together in 85 staggered relation to form a core, said units having additional depressions formed in their strips inside and adjacent the said shoulders to provide supports for said core transverse thereof, in addition to said 90 raised edge portions, said depressions extending transverse the units and set abutting each other, said extra depressions being formed also with intermediate return bends to provide for vertical passage of air 95 through said units.

3. A radiator formed of corrugated metal in honey-comb type and having expanded ends for the corrugations, and air passages horizontally of the radiator, and water passages vertically thereof, with the expanded ends of the corrugations at some points more deeply drawn than at others whereby the water passages are extended in width by interspaced extra extensions of the corrugations, as and for the purpose described.

4. A radiator formed of corrugated metal in honey-comb type and having expanded ends for the corrugations, air passages horizontally of the radiator and water passages 100 vertically thereof, with the water passages extended in width by interspaced extra deep drawing of the expanded ends of the corrugations of the radiator and constricted by intermediate corrugations of the metal 110 intermediate the ends.

EDWARD B. CORCORAN.
